DESIGN FOR A COMBINED SHIPPING AND DISPLAY CONTAINER

Daniel A. Larkin, Sandusky, Ohio, assignor to The Hinde & Dauch Paper Company, Sandusky, Ohio

Application March 18, 1942, Serial No. 196,235

Term of patent 7 years

To all whom it may concern:

Be it known that I, Daniel A. Larkin, a citizen of the United States and a resident of Sandusky, county of Erie, and State of Ohio, have invented a new, original, and ornamental Design for a Combined Shipping and Display Container, of which the following is a specification, reference being had to the accompanying drawing, forming a part thereof.

The figure is a perspective view of a combined shipping and display container, showing my new design. The back of the article illustrated is plain and the side not shown is a substantial duplicate of that shown in the figure.

I claim:

The ornamental design for a combined shipping and display container, as shown and described.

DANIEL A. LARKIN.
